B. J. DOWD,
PLATEN RELEASE MECHANISM,
APPLICATION FILED APR. 9, 1917.

Patented Nov. 20, 1917.

UNITED STATES PATENT OFFICE.

BERNARD J. DOWD, OF HARTFORD, CONNECTICUT, ASSIGNOR TO ROYAL TYPEWRITER COMPANY, INC., OF NEW YORK, N. Y., A CORPORATION OF NEW YORK.

PLATEN-RELEASE MECHANISM.

1,247,383.

Specification of Letters Patent. Patented Nov. 20, 1917.

Application filed April 9, 1917. Serial No. 160,607.

To all whom it may concern:

Be it known that I, BERNARD J. DOWD, a citizen of the United States, and a resident of Hartford, in the county of Hartford and State of Connecticut, have invented certain new and useful Improvements in Platen-Release Mechanism, of which the following is a specification.

The present invention relates generally to shifting mechanism, particularly of the character applicable to typewriting machines.

Owing to oft-repeated manipulation in the usual operation of devices of this kind, certain parts are, of necessity, subjected to stresses which eventually require that these parts be replaced. It is an object of this invention to so construct the shifting device as to necessitate the least amount of dismantling of it when repairing the same, and to permit of replacements being made by the removal of the least number of parts and by parts which are inexpensive and readily inserted in or removed from the structure as a whole.

In the embodiment of the invention herein disclosed, it is shown in connection with a so-called fractional spacing device of the character set forth in the Hess Patent No. 1,196,110 of August 29, 1916. In that patent, the line spacing mechanism includes a pair of locking members between the platen or platen shaft and the usual ratchet. One of these locking members is shiftable or movable lengthwise with respect to the platen shaft by an actuating device, preferably extending through the platen shaft itself, and adapted to engage with said locking member. When the locking member is so moved, fractional spacing may be effected. This invention deals chiefly with an abutment member, independent of the shiftable or movable locking member, but easily inserted in or removed from said locking member.

The main feature of the invention resides in a shiftable or movable member which is provided with a removable abutment member, frictionally seated in the shiftable member, and having a projecting portion which is engaged by the actuating means for shifting the movable member.

The invention further resides in a fractional spacer for typewriting machines, which includes a movable disk-like member

provided with a removable abutment member frictionally seated in the face of the movable member.

The invention still further consists of a platen release mechanism in which the line spacing mechanism includes locking members, one of which is movable lengthwise of the platen shaft to permit of fractional spacing, together with actuating means for said locking member extending lengthwise of the platen shaft, and a removable intermediate abutment member held frictionally in the movable locking member and having a projection extending into the path of movement of the actuating means.

The removable abutment member is of a resilient character and of annular contour and is provided with an inwardly projecting tongue. In the particular form here disclosed it consists of a split ring having an inwardly projecting tongue and provided with a tapered face which is complementary to a tapered undercut recess in the face of the disk-like movable member.

Also, in the embodiment herein disclosed the platen shaft is provided with a channel into which the tongue of the abutment member extends and in which the actuating means for the movable member operates.

In the accompanying drawings: Figure 1 is a view partly in elevation and partly in section of a platen and release mechanism for the same, showing my invention applied in a preferred embodiment.

Fig. 2 is a sectional view similar to Fig. 1 with the portion in elevation omitted and with certain parts omitted, the section through the platen and associated devices being taken at an angle to that shown in Fig. 1.

Fig. 3 is a transverse sectional view on the line 3—3 of Fig. 2.

Fig. 4 is a detail view of the abutment member.

5 indicates a platen of a conventional type consisting here of a core 6 and a rubber covering 7. One end of the platen is provided with a head 8 having an inwardly extending hollow boss 9 and an outwardly extending hollow boss 10. The head 8 is secured to the platen by means of the screws 11 as shown. 12 is the platen shaft here shown as being secured to the platen by means of the set screw 13.

A typical line spacing mechanism is here

shown consisting essentially of two locking members 14 and 15 and the ratchet 16. The locking member 15 is mounted to rotate freely on the platen shaft 12, and the ratchet 16 is mounted on the hub 17 of the locking member 15 and turns therewith. The locking member 14 is slidably mounted on the hollow boss 10 of the head 8 and is connected with the platen so as to turn there-
 10 with. In the present instance, the member 14 is of a disk-like character, but is nevertheless of ample dimensions or thickness to make it durable and to give it sufficient strength to withstand the stresses to which it is subjected. In the form herein disclosed the member 14 consists of a hub portion 18 and preferably three outwardly extending arms 19. The peripheral surfaces 20 of these arms are slightly inclined in-
 15 wardly as shown and are provided with fine serrations or teeth which engage with oppositely inclined serrations or teeth on the annular member 21 of the locking member 15 for the purpose of obtaining fractional spacing as described in the Hess Patent No. 1,196,110. The locking member 14 is mounted to rotate with the platen and is normally urged into engagement with the locking member 15 by suitable means, which,
 20 in the present instance, take the following form: 22 indicate pins, suitably secured to the arms of the locking member 14, and having extensions 23 which pass snugly through openings 24 in the head 8 and into sockets 25 of the platen. 26 indicates a spring which is seated between the inner end of the socket 25 and the collar 27 carried by extension 23. The collar 27 is situated part way down the extension 23 so that the end of the exten-
 25 sion 23 projects inside the spring 26. The connection just described constitutes in effect spring-pressed plungers which normally urge the locking member 14 into engagement with the locking member 15 and which at the same time insure the rotation in unison of the locking member 14 and the platen.
 One face 28 of the locking member 14 is provided with an annular recess 29 having a tapered undercut 30 as shown. In this 30 tapered undercut is seated an abutment member 31 here shown as a split ring having its outer peripheral face 32 tapered as shown to correspond to the tapered undercut 30 of the recess. This member 31 is pro-
 35 vided with an inwardly projecting tongue 33 which projects through the open channel 34 of the hollow boss 10 and extends into the channel 35 of the platen shaft 12. Suitable actuating means, here shown as a rod 36, ex-
 40 tends through the channel in the platen shaft 12 and is operated from the end of the same by means of the push button 37. It will be observed that the end of the rod 36 comes in contact with the tongue 33 of the 45 abutment member and receives the thrust of
 the same when it is desired to disengage the locking members 14 and 15. The abutment member 31 is frictionally seated in the recess 29 and when so seated is held in place by its resiliency, the tapered faces 30 and 32 co-
 operating to lock the parts together. It will be readily understood that, if for any reason it is desired to renew the abutment member 31, it can be accomplished merely by contracting the split ring and sliding it out of the recess 29 and that another member can be substituted in place thereof without materially dismantling the parts. The split ring therefore serves the threefold purpose of permitting its insertion, retention and re-
 50 removal from the locking member 14. In practice it has been found advantageous to form the split ring and tongue in one piece, and to have the tongue circumferentially opposite to the split in the ring, as shown in Fig. 4, since the location of the tongue at this point tends to reinforce the abutment member as a whole and serves to give it a definite and relatively rigid point from which its free ends may expand.
 As is customary in devices of this character, the platen shaft 12 is provided with a suitable knob or twirler 38, the bushing 39 of which overhangs the ends of the platen shaft and is secured to the platen shaft as by the set screw 40. The outer end of the bushing 39 is here slightly enlarged interiorly as at 41 to afford space for the stop member 42 carried by the rod 36 and push button 37. The inward movement of the push button 37 is limited by the stop member 42 coming in contact with the end of the platen shaft, and its outward movement is limited by the set screw 43. 44 indicates, in a general way, suitable framework for the device.
 Normally the locking members 14 and 15 are in engagement with each other owing to the action of the springs 26, and, when so engaged, the ratchet 16 and the platen 5 are connected so that the device may be operated as a line spacing mechanism in a manner well known in the art. When it is desired to obtain fractional spacing, the push button 37 is pressed inwardly thereby causing the end of the rod 36 to engage the tongue 33 of the abutment member 31 and effecting a movement of the locking member 14 out of engagement with the locking member 15. This releases the platen 5 from the ratchet 16. At such times, therefore, the platen may be turned fractional distances by operating the twirler 38 in either direction. When pressure is removed from the push button 37, the springs 26 immediately cause the locking member 14 to be moved into engagement with the locking member 15 in their newly adjusted position without slippage of the parts owing to the fine serrations or teeth at 20 and 21.

I claim:

1. Shifting mechanism comprising: supporting means, a member shiftable with respect to said supporting means, an annular resilient abutment member removably seated in said shiftable member and held frictionally by its resilience, said abutment member having a projecting portion, and means for engaging the projecting portion to move the shiftable member.

2. Shifting mechanism comprising: supporting means, a member shiftable with respect to said supporting means and having an undercut recess, an annular resilient abutment member, having an inwardly projecting tongue, removably seated in said recess and held there by friction, and means for engaging the projecting tongue to move the shiftable member.

20 3. Shifting mechanism comprising: supporting means, a member shiftable with respect to said supporting means and having a tapered undercut recess, a split ring of resilient material, having a tapered face complementary to the taper of the recess, seated in said recess, said ring being split to permit of its insertion, retention and removal, and said ring having further an inwardly projecting tongue, and means for engaging the projecting tongue to move the shiftable member.

4. Shifting mechanism comprising: supporting means, a member shiftable with respect to said supporting means and having a tapered undercut recess, a split ring of resilient material, having a tapered face complementary to the taper of the recess, seated in said recess, said ring being split to permit of its insertion, retention and removal; and said ring having further an inwardly projecting tongue formed integrally therewith and located circumferentially opposite to the split in the ring, and means for engaging the projecting tongue to move the shiftable member.

45 5. A fractional spacer for typewriting machines including: a movable disk-like member, and an annular resilient abutment member removably seated in the face of said movable member and held frictionally by its resilience, said abutment member having a projecting portion.

55 6. A fractional spacer for typewriting machines including: a movable disk-like member having an undercut recess in its face, and an annular resilient abutment member, having an inwardly projecting tongue, removably seated in said recess and held there by friction.

60 7. A fractional spacer for typewriting machines including: a movable disk-like member having a tapered undercut recess in its face, and a split ring of resilient material having a tapered face complementary to the taper of the recess, seated in said

recess, said ring being split to permit of its insertion, retention and removal, and having further an inwardly projecting tongue.

8. A fractional spacer for typewriting machines including: a movable disk-like member having a tapered undercut recess in its face, and a split ring of resilient material having a tapered face complementary to the taper of the recess, seated in said recess, said ring being split to permit of its insertion, retention and removal, and having further an inwardly projecting tongue formed integrally therewith and located circumferentially opposite to the split in the ring.

29 9. Platen release mechanism for typewriting machines comprising: a platen shaft, line spacing mechanism including locking members, one of which is movable lengthwise with respect to the platen shaft to permit of fractional spacing, actuating means extending lengthwise of the platen shaft for effecting the lengthwise movement of the locking member, and an intermediate annular resilient abutment member removably seated in said movable locking member and held frictionally by its resilience, said abutment member having a portion extending into the path of movement of the actuating means.

85 10. Platen release mechanism for typewriting machines comprising: a platen shaft, line spacing mechanism including locking members, one of which is of disk-like formation with an undercut recess in its face and movable lengthwise with respect to the platen shaft to permit of fractional spacing, actuating means extending lengthwise of the platen shaft for effecting the lengthwise movement of the locking member, and an annular resilient abutment member, having an inwardly projecting tongue, removably seated in said recess and held there by friction.

105 11. Platen release mechanism for typewriting machines comprising: a platen shaft having a longitudinal channel, line spacing mechanism including locking members, one of which is of disk-like formation with a tapered undercut recess in its face and movable lengthwise with respect to the platen shaft to permit of fractional spacing, a split ring of resilient material having a tapered face complementary to the taper of the recess, seated in said recess, said ring being split to permit of its insertion, retention and removal, and having further an inwardly projecting tongue extending into the channel of the platen shaft, and actuating means extending lengthwise in the channel of the platen shaft for engaging the inwardly projecting tongue.

115 12. Platen release mechanism for typewriting machines comprising: a platen shaft having a longitudinal channel, line spacing

mechanism including locking members, one of which is of disk-like formation with a tapered undercut recess in its face and movable lengthwise with respect to the platen shaft to permit of fractional spacing, a split ring of resilient material having a tapered face complementary to the taper of the recess, seated in said recess, said ring being split to permit of its insertion, retention and removal, and having further an inwardly projecting tongue formed integrally therewith and located circumferentially opposite to the split in the ring and

extending into the channel of the platen shaft, and actuating means extending 15 lengthwise in the channel of the platen shaft for engaging the inwardly projecting tongue.

Signed at Hartford, in the county of Hartford and State of Connecticut, this 20 fifth day of April, 1917.

BERNARD J. DOWD.
